LOCK DEVICE FOR WELL TOOLS

Reuben C. Baker, Coalinga, Calif., assignor to
 Baker Oil Tools, Inc., Vernon, Calif., a corpora-
 tion of California

Application February 10, 1943, Serial No. 475,390

5 Claims. (Cl. 166—12)

This invention relates to well tools, and more particularly to the locking portion of such tools designed for sub-surface operations in well bores.

Locking devices are used in connection with many tools designed for operations in well bores. One of the most common of such devices is a J pin and slot arrangement employed with packers, liner hangers, tubing anchors, well washers, etc. Such J, L, and similar types of locks can function to maintain certain well tool parts in a definite relative position, or they can be manipulated to release such parts and permit their performance of the particular action or operation in the well bore, such as to set a packer or liner therein, control a valve, etc.

In locking and unlocking these J or L devices, it is necessary to turn the string of tubing to which the tool is attached either to the right or to the left. Tubing or drill pipe strings are usually made up of sections connected together by right hand threaded joints. Occasionally a set of left hand threads may be employed. Regardless of the type of threaded connection availed of, the turning of the tubing string in one direction to manipulate the J or L lock will tend to tighten the threaded joints of the tubular string, but the turning of such string in the other direction tends to unscrew and possibly disconnect it at one or more of the joints. This is particularly true when the tool is operated in a crooked hole, or under conditions in the well bore which can freeze the tool therein, making it necessary to impose a comparatively large torque on the tubular string in order to operate the locking device.

It is an object of the present invention to overcome the aforementioned difficulties by providing a well tool whose parts can be locked or relocked without the necessity for turning the tubular string in a direction in which its joints might become loosened or unscrewed from one another.

Still another object of the invention resides in the provision of a J or L type of locking device in which the parts can be moved to locked and unlocked positions through rotation of the tubular string in the same direction.

A further object of the invention is to prevent inadvertent movement of a J or L type of locking device to unlocked position.

The invention has other objects that will become apparent from a consideration of the embodiment shown in the drawings accompanying and forming a part of the present specification. This form will now be described in detail, but it is to be understood that such detailed description

is not to be taken in a limited sense, since the scope of the invention is best defined by the claims appended hereto.

Referring to the drawings:

Figure 1 is a longitudinal view, partly in section and partly in elevation, of a well packer embodying the present invention with its parts in retracted position for movement in a well bore or casing;

Figure 2 is a view similar to Figure 1, disclosing the well packer with its parts in packed off condition within the well casing;

Figure 3 is a longitudinal section on a large scale of part of the device illustrated in Figure 2;

Figure 4 is a cross section taken along the line 4—4 in Figure 3;

Figures 5 to 8, inclusive, are diagrammatic views of the locking device in different operative positions;

Figure 9 is a view similar to Figure 3, with parts of the lock device in another operative position; and

Figure 10 is a perspective of the slot portion of the lock device.

The invention is exemplified in the drawings as forming part of a well packer of the retrievable type. It is to be understood, however, that the invention is also applicable to other well tools, as the following detailed description of the apparatus shown in the drawings will bring out.

The packer illustrated in the drawings is specifically described and particularly claimed in my application for "Releasable well packers," Serial No. 419,061, filed November 14, 1941, now Patent No. 2,368,400, granted Jan. 30, 1945. This packer A is adapted to be run in a well bore or casing B on the end of a tubular string C threadedly or otherwise attached to the upper end of the tubular mandrel 10 of the packer. The lower end of this mandrel is threaded into the upper end of a tubular packer body 11, to the lower end of which is secured a packing actuator 12 in the form of a guide.

A tapered expander 13 mounted on the body is preferably prevented from turning with respect thereto by a key 14 secured to the exterior of the body 11 and received within a keyway 15 in the expander, so as to permit relative longitudinal movement between the body and expander, while preventing rotation therebetween. When the tubular string C, mandrel 10 and body 11 are elevated, the packing actuator 12 is moved towards the expander 13 to compress an intervening packing sleeve 16 surrounding the body and force it outwardly to effect an annular seal between the

body 11 and casing B. Such actuation of the packing sleeve 16 only occurs when the tapered expander 13 is prevented from moving upwardly, which results from anchoring engagement by a plurality of slips 17, cooperating with the tapered expander, with the wall of the casing. The slips 17 have tapered surfaces 18 cooperable with companion tapered surfaces 19 on the expander, the inclination of such surfaces being such as to move the slips 17 outwardly toward the casing upon elevation of the expander 13. Conversely, lowering of the expander with respect to the slips permits the latter to release from anchoring engagement with the wall of the casing and move inwardly to retracted position.

It is therefore apparent that elevation of the tubular string C, mandrel 10 and packer body 11 can effect anchoring of the tool through engagement of the slips 17 with the casing under the influence of the tapered expander 13, and they can also effect compression of the packing sleeve 16 between the expander 13 and guide 12 to produce its radial outward expansion into sealing engagement with the wall of the casing.

The slips 17 are held together for joint movement along the tapered expander 13 to and from engagement with the casing by providing recesses 20 in their side faces, which receive outwardly extending fingers 21 for guiding the slips to and from the casing and for preventing their longitudinal movement except in unison by engaging the ends of the recesses 20. These fingers 21 are integral with a sleeve 22 slidable on the mandrel 10, which has a stop ring 23 secured thereto by screws 24 or the like for the purpose of limiting the extent of outward movement of the slips.

This sleeve 22, and the slips 17 assembled thereon, are coupled to a drag and lock device 25, comprising a lower collar 26 slidable on the mandrel 10, which receives the lower ends of a plurality of circumferentially spaced outwardly bowed springs 27 held thereagainst in assembled relation by a ring 28 fastened to the collar by a plurality of screws 29. These springs are disposed around the mandrel with their upper ends secured to an upper drag collar 30 by an upper ring 31 suitably fastened thereto, as by screws 32.

The drag and lock device 25 is coupled to the slip assembly by means of a sectional tie or coupling ring 33 secured to the lower collar 26 by screws 34, and having a lower inturned flange 35 receiving and fitting under an external flange 36 at the upper end of the slip sleeve 22. Rotation of the tubular string C, mandrel 10 and drag device 25 is permitted without corresponding rotation of the slip assembly sleeve 22 and slips 17, due to the swivel type of action provided by the lower end of the coupling ring 33 and sleeve flange 36.

It is to be noted that the drag device 25 engages the casing wall and thereby tends to resist longitudinal movement of the slips 17 coupled thereto through the well casing. Upon reaching the desired setting point in the casing, if the tubular mandrel 10 is permitted to move upwardly with respect to the drag device, such elevation would also elevate the body 11 of the packer, and through the guide 12 and packing sleeve 16 elevate the expander 13 within the slips 17, since the latter are prevented from moving upwardly by the drag device, to force the slips radially outward into anchoring engagement with the casing wall. A continuation of such upward movement causes compression of the packing sleeve 16 into sealing engagement with the casing B and body 11, in the manner hereinbefore described. Con-

versely, lowering of the tubular mandrel 10 with respect to the drag device 25 permits retraction of the packing sleeve 16 from the casing wall and produces corresponding downward movement of the tapered expander 13, through engagement of the body shoulder 37 with the expander flange 38, so that the slips 17 are movable inwardly to retracted position, since they are prevented from moving longitudinally by the drag device.

It is important to note that upward movement of the tubular mandrel 10 and body 11 can effect anchoring of the packer in packed off condition within the well casing, and that lowering of these members can effect release of the packer. It is, therefore, essential that some means be provided for preventing relative movement between the slips 17 and the tapered expander 13 in order to allow the tubular mandrel 10 to be elevated without anchoring the tool in the well casing when the entire tool is to be raised within the well casing.

The usual device for locking slips with respect to an expander, or for that matter, for preventing relative movement until desired between cooperative parts of sub-surface well tools generally, is a J type of lock. Such lock can include a pin operable within a longitudinal slot and an intersecting horizontal slot. When the pin is positioned in the horizontal slot the tool members are locked, and when the pin is positioned in the longitudinal slot, the tool members are unlocked and the tool may be manipulated in the desired fashion, depending upon its design and the purpose for which it is to be used. However, movement of the pin within the horizontal slot to and from the longitudinal slot (or to and from locking and unlocking positions) is performed through turning or rotation of the tubular string to which the tool is attached in a clockwise or counterclockwise direction. Assuming that the tubular string is made up of right hand thread connected joints, its rotation in a clockwise direction would tend to tighten the joints, while rotation in the opposite or counterclockwise direction would tend to loosen the joints. That is one of the difficulties with this type of pin and slot arrangement. It requires counterclockwise or left hand turning of the tubular string for its effective and complete operation.

The present invention overcomes this disadvantage and difficulty through its ability to effect locking and unlocking of the device and the slips 17 through turning of the tubular string in one direction only. In the case of a tubular string in which the threaded joints are right hand, such turning takes place in a clockwise direction. It is apparent, however, that the locked device could be so designed as to operate upon turning in a counterclockwise direction only, where a left hand threaded tubular connection is employed.

As disclosed in the drawings, the locking device 39 is incorporated in the lower portion of the drag device 25. A sleeve 40 extends upwardly from the lower collar 26 and is spaced therefrom to form a circumferentially continuous slot or groove 41 completely around the mandrel 10 which is disposed substantially entirely in a horizontal position. This sleeve has a longitudinal slot 42 extending upwardly from the circumferential slot to permit upward sliding of the mandrel 10 therewith whenever a locking pin 43 on the mandrel is positioned in the longitudinal slot portion. The sleeve 40 is maintained in proper spaced relation with respect to the lower collar 26 and is secured for movement therewith by suitable means, as by

welding a ring 44 on the sleeve and bridging the circumferential slot 41 formed between the sleeve 40 and lower drag collar 26 by a spider like ring 45, whose upper end is welded to the first mentioned ring 44, and whose lower end is welded or otherwise suitable secured to the lower collar 26.

The mandrel lock pin 43 is movable in the longitudinal slot portion 42 and also in the circumferentially continuous slot portion 41 of the locking device. It is apparent that when the mandrel 10 has been lowered with respect to the drag device 25 in order to position the pin 43 in the circumferentially continuous slot 41, the tool A is in locked position and the slips 17 and packing sleeve 16 will be retained in retracted position, allowing the tool to be moved longitudinally in either direction through the casing B. However, the turning of the tubular string C and mandrel 10 to align the pin 43 with the longitudinal slot portion 42 allows the tubular string C to be moved upwardly to set the slips 17 and packing 16 against the casing wall.

It is to be noted that the circumferentially continuous slot 41 does not all lie in a single transverse plane, but that the upper end of the lower collar 26 is formed with an upwardly extending step 46 cooperating with a companion upwardly extending recess 47 in the lower end of the sleeve 40 to form an upper or elevated portion 48 of the slot 41, raised a substantial distance above its lower portion 49. However, these slot portions 48, 49 are communicable with each other to permit passage of the pin 43 on the mandrel 10 from one slot portion into the other. The difference in elevation between these slot portions is insufficient to cause material movement of the packer parts when the mandrel 10 is elevated to shift the pin 43 from the lower slot portion 49 to the upper slot portion 48, so that the slips 17 and packing 16 are moved only slightly and will remain in comparative retracted position.

Both the upper and lower slot portions 48, 49 merge into the longitudinal slot 42, but at different elevations. The upper slot portion 48 lies in a transverse plane which intersects the left hand wall 50 of the longitudinal slot 42. It is apparent that when the lock pin 43 is positioned in the upper slot 48, rotation of the mandrel 10 in a clockwise direction will cause the pin 43 to move within this upper slot in the same direction until it enters the longitudinal slot 42 and strikes against the lefthand wall 50 of the latter. When this position is reached, the operator is notified of that fact, usually by the feel of the tubular string C. In any event, he knows that the turning of the tubular string C and mandrel 10 a partial revolution positions the pin 43 against the lefthand wall 50 of the longitudinal slot. The operator may then elevate the tubular string and mandrel, since the pin 43 is free to move upwardly in the longitudinal slot 42, to cause setting of the packer parts, as described above.

When the tool is to be released and the packer parts returned to retracted position, the tubular string C and mandrel 10 are lowered with respect to the drag device 25, as permitted by lowering of the lock pin 43 within the longitudinal slot 42, until the pin is at the intersection between the longitudinal slot 42 and the lower circumferential slot portion 49. Turning of the tubular string and mandrel in a clockwise direction, or to the right, moves the pin 42 into the lower circumferential slot portion 49, in which the slips

17 and packing 16 are locked in retracted position. If it is again desired to set the packer, the tubular string and mandrel are rotated in a clockwise direction to move the pin 43 to the other end of the lower slot portion 49, after which the tubular string C is elevated very slightly to lift the pin 43 into the upper slot portion 48. Further rotation of the tubular string and mandrel shifts the pin 43 into the longitudinal slot 42 as determined by engagement of the pin with the left wall 50 of the latter.

The operation of the pin and slot combination is exemplified diagrammatically in Figures 5 to 8, inclusive. These views each disclose the 360° circumferentially continuous slot 41 laid out on a plane. Actually, of course, this plane represents the cylindrical portion of the sleeve 40 and collar 26 in which the right and left ends of the plane join to complete the cylinder. Each view shows the longitudinal slot 42, and the upper and lower portions 48, 49 of the circumferentially continuous slot 41. The left end of the upper slot portion 48 merges into the longitudinal slot 42 opposite the left wall 50 of the latter, while the lower portion 49 of the circumferentially continuous slot extends to the left from the bottom end of the longitudinal slot 42. The upper and lower slot portions 48, 49 are communicable with one another at a substantial angular distance from the longitudinal slot 42.

Figure 5 discloses the lock pin 43 in its locked position within the lower circumferential slot portion 49. When it is desired to move the pin 43 into its releasing position within the longitudinal slot 42, the tubular string C and mandrel 10 are turned in a clockwise direction so as to move the pin 43 along the lower slot portion 49, thence a slight distance upwardly into the upper slot portion 48, as exemplified in Figure 6, and thence into the longitudinal slot 42 with the pin 43 engaging its left wall 50 (as illustrated in Figure 7). The mandrel 10 may now be moved longitudinally, as permitted by a corresponding movement of the pin 43 in the longitudinal slot 42 (Figure 8).

When the tool is to be relocked, the mandrel 10 is lowered to move the pin 43 downwardly until it moves from the longitudinal slot 42 into the lower portion 49 of the circumferential slot 41. Partial rotation of the mandrel 10 and tubular string C in a clockwise direction will reposition the pin 43 in this latter circumferential slot portion, as shown in Figure 5.

It is therefore apparent that the pin 43 may be moved from locked to unlocked position, and back to locked position, through rotation of the tubular string C and mandrel 10 in the same single direction, which in the above example is a clockwise direction.

In order to preclude inadvertent retrograde movement or rotation of the pin 43 into alignment with the longitudinal slot 42, a one-way latch is incorporated in the device, so that unintentional setting of the packer A is prevented while it is being elevated within the well bore. This latch is of such character as to permit movement of the pin 43 from the longitudinal slot 42 downwardly into the lower portion 49 of the circumferential slot 41, but it prevents return movement of this pin 43 from the lower circumferential slot 49 back into the longitudinal slot 42. The only way that the pin can progress into the longitudinal slot is through its rotation in a clockwise direction, so that it must first enter the upper circumferential slot portion

48 before being permitted to enter the longitudinal slot 42.

The one-way latch device disclosed in the drawings consists of a leaf spring 51 whose upper end is mounted on a collar 52 suitably secured, as by welding, to the upper end of the sleeve 40. This spring 51 is held in position on its collar 52 by an encircling ring 53 secured to the latter member by one or more screws 54. The spring 51 depends from the collar 52 lengthwise over the longitudinal slot 42, being spaced a sufficient distance from the sleeve 40 to permit free longitudinal movement of the pin in this slot, as will be clear from an inspection of Figure 3. The lower end of the spring extends into a recess 55 in the lower sleeve 45 connecting the upper sleeve 40 with the lower drag collar 26, and has an inturned nose 56 projecting into the juncture 57 of the longitudinal slot 42 with the lower portion 49 of the circumferential slot 41.

The pin 43 is free to move lengthwise along the longitudinal slot 42 without restraint from the one-way spring latch 51. However, lowering of the mandrel 10 and pin 43 sufficiently causes the pin to engage the inturned nose 56 at the lower end of the latch, forcing this latch 51 in an outward direction and allowing the pin 43 to enter the lower portion 49 of the circumferential slot 41. A slight turn of the mandrel 10 and pin 43 in a clockwise direction causes the pin to move in the lower circumferential slot portion 49 away from the spring latch 51 and permits the latter member to spring back into position with its inturned nose 56 extending across the end 57 of the lower circumferential slot portion 49 (see Figure 5).

If the mandrel 10 and pin 43 were now to be turned in a counterclockwise direction, the inturned nose 56 of the spring latch would block the entry of the pin 43 back into the longitudinal slot 42. The only way for this pin to again enter the longitudinal slot is to rotate the mandrel 10 to which it is attached in a clockwise direction, causing it to move from the lower slot portion 49 into the upper slot portion 48 and thence into the longitudinal slot 42. However, when the placing of this pin in locked position is again desired, the mandrel 10 need merely be lowered to cause the pin 43 to engage the inturned latch nose 56, forcing it out of the way and allowing the pin to reenter the lower slot portion 49.

It is, therefore, apparent that the one-way latch precludes return movement of the pin 43 from its locked position back into the longitudinal slot 42. Almost a complete rotation of the tubular string C is required in a clockwise direction before this pin can again be located in the longitudinal slot. Such complete rotation will not occur inadvertently while the tool is being moved through the well bore either in an upward or downward direction. The step 46 between the upper and lower slot portions 48, 49 assists in preventing unintentional positioning of the pin 43 in the longitudinal slot 42, since it is necessary to elevate the tubular string C and mandrel 10 a slight distance in moving from the lower portion 49 to the upper portion 48. Unless such elevation takes place, the pin 43 when in the lower slot portion 49 merely strikes against the left side of the lower slot 49 without being permitted to enter the upper slot portion 48.

I claim:

1. A well tool having relatively movable parts, means for controlling longitudinal movement of said parts with respect to one another, including

a first member connectable to a running-in string and attached to one of said parts, a second member attached to another of said parts, one of said members surrounding the other, one of said members being provided with a pin and the other of said members with a longitudinal slot and a circumferential slot disposed substantially entirely in a horizontal position and whose extremities merge into said longitudinal slot, said pin being movable along the entire extent of said circumferential slot upon relative rotary movement between said members while preventing substantial longitudinal movement between said parts, and said pin being movable along said longitudinal slot upon movement of said first member by said running-in string to permit longitudinal movement of said parts with respect to each other.

2. A well tool having relatively movable parts, means for controlling longitudinal movement of said parts with respect to one another, including a member connectable to a running-in string and attached to one of said parts, a drag device engageable with the wall of the well casing and within which said member is movable, said drag device being attached to another of said parts, a pin fixed to said member, said device being provided with a longitudinal slot and a circumferential slot disposed substantially entirely in a horizontal position and whose extremities merge into said longitudinal slot, said pin being movable along the entire extent of said circumferential slot upon rotary movement of said member by said running-in string while preventing substantial longitudinal movement between said parts, and said pin being movable along said longitudinal slot upon movement of said member by said running-in string to permit longitudinal movement of said parts with respect to each other.

3. A well tool having relatively movable parts, means for controlling longitudinal movement of said parts with respect to one another, including a first member connectable to a running-in string and attached to one of said parts, a second member attached to another of said parts, one of said members being provided with a pin and the other of said members with a longitudinal slot and a circumferential slot disposed substantially entirely in a horizontal position and whose extremities merge into said longitudinal slot, and means for preventing passage of said pin from said circumferential slot to said longitudinal slot upon relative rotary movement between said members in one direction, while permitting such passage upon their relative movement in another direction.

4. A lock device adapted to be lowered in a well bore for controlling the operation of a well tool therewithin, including means providing a longitudinal slot and a circumferential slot whose extremities communicate with said longitudinal slot at different elevations, a member movable with respect to said means, said member having a pin movable relatively along the entire extent of said circumferential slot and also along said longitudinal slot, and a one-way latch device shiftable by said pin from its path of movement for permitting passage of said pin from said longitudinal slot into said circumferential slot upon relative movement between said means and member in one direction but which prevents retrograde movement of said pin from said circumferential slot into said longitudinal slot upon

relative movement between said means and member in another direction.

5. A well tool adapted for operation in a well bore, including a first member connectable to a running-in string for moving said tool within said well bore, a second member movable with respect to said first member, one of said members surrounding the other, one of said members being provided with a pin, and the other of said members with a longitudinal slot and a circumferential slot disposed substantially entirely in a horizontal position and whose extremities merge into said longitudinal slot, said pin being mov-

able along the entire length of said circumferential slot and along said longitudinal slot upon movement of said first member by said running-in string, and a one-way latch device for preventing movement of said pin from said circumferential slot into said longitudinal slot upon rotation of said first member by said running-in string in one direction, but which permits passage of said pin from said longitudinal slot into said circumferential slot upon rotation of said first member by said running-in string in the other direction.

REUBEN C. BAKER.
